Primary Examiner — Natasha Vujcic*Assistant Examiner* — Christina Gabrielle Cosden(74) *Attorney, Agent, or Firm* — Foley & Lardner LLP(57) **CLAIM**

The ornamental design for a key safe as shown and described.

DESCRIPTION

FIG. 1 is a front, left, top perspective view of the claimed design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The ornamental design that is claimed is shown in solid lines in the drawings. The portions of the key safe depicted in broken lines form no part of the claimed design.
